UNITED STATES PATENT OFFICE.

JOHN ISRAEL NEWBURG, OF VICKSBURG, MISSISSIPPI.

CAR-FENDER.

SPECIFICATION forming part of Letters Patent No. 603,339, dated May 3, 1898.

Application filed October 20, 1897. Serial No. 655,831. (No model.)

To all whom it may concern:

Be it known that I, JOHN ISRAEL NEWBURG, a citizen of the United States, residing at Vicksburg, in the county of Warren and State 5 of Mississippi, have invented certain new and useful Improvements in Car-Fenders; and I do declare the following to be a full, clear, and exact description of the invention, such as will enable others skilled in the art to which it applies 10 to make and use the same.

My invention relates to wheel-fenders for use on motor-cars, and will be fully understood from the following description and claim when taken in conjunction with the 15 annexed drawings, in which—

Figure 1 is a side elevation, partly in section, illustrating my improved fender in its operative position upon a portion of a car-body. Fig. 2 is a horizontal section taken in 20 the plane indicated by the line $y-y$ of Fig. 1; and Figs. 3 and 4 are enlarged detail sections taken in the planes indicated by the lines $w-w$ and $x-x$, respectively, of Fig. 1.

In the said drawings similar letters designate 25 corresponding parts in all of the several views, referring to which—

A designates a car-body having an ordinary platform a , and B designates hangers, two of which are arranged adjacent to each side of 30 the car-body, as shown. In each of these hangers B are placed two peripherally-grooved wheels C, which are arranged one above the other and are disposed in the direction of the length of the car, as shown. The forward 35 and rear pairs of wheels C are arranged in longitudinal alinement with the forward pairs of wheels in a plane slightly below that of the rear pairs for a purpose presently described, and the upper and lower wheels are 40 designed to receive rods D between them. The said rods D are provided with apertures b for the detachable connection of the fender proper, (presently described,) and they are backed by springs E, so as to enable the 45 fender proper to give rearwardly when it strikes a person on the track, and thus reduce the liability of such person being seriously injured. In the present embodiment of my invention the springs E are connected at one 50 end to hangers c, depending from the car-platform a , and are connected at their opposite ends to arms d, adjustably fixed on the

rods D by set-screws e, such adjustable connection being provided so that the tension of the springs may be increased or diminished, 55 as desired. The springs E will tend to normally hold the rods and fender proper in the position shown and will return the same to such position when they have been passed rearwardly, and in this they will be assisted by 60 the downward inclination of the rods D.

I contemplate equipping each end of the car-body with the devices thus far described and detachably connecting the fender proper to the rods D, so that said fender proper may 65 be used upon either end of the car, according to the direction in which the same is to travel.

F designates the fender proper, which comprises a frame f, made up of two sections g h 70 and netting or other suitable textile material i. The frame-section g comprises tubular side bars j, which are designed to receive the rods D and be detachably connected thereto by the pivoted hooks k, the arms l, which are 75 formed integral with and extend upwardly and rearwardly from the bars j and having swiveled threaded unions m at their upper ends, and the upper cross-bar n, which has depending branches p, with threaded ends for 80 the engagement of the unions m, as shown.

The forward ends of the side bars j of the frame-section g are flattened, as shown, and provided with lateral lugs r. To these flattened ends are pivotally connected by bolts s 85 the rear flattened ends of the side bars t of the frame-section h, said section being supported in its operative position by the lugs r, which, however, do not interfere with it being swung back upon the section g when desired. 90 The side bars t of the section h are connected adjacent to their forward ends by a cross-bar u, and they are provided at their forward ends with eyes v, which receive the journals of a rubber-covered roller w, the purpose of 95 which is to facilitate the picking up of a person on the track and preventing injury to such person.

It will be seen from the foregoing that my improved fender proper is very cheap and 100 simple and that it may be quickly and easily made and applied to a car.

It will also be seen that the fender as a whole will tend to pick up a person on the

track without inflicting any serious injury on such person.

Having thus described my invention, what I claim is—

- 5 The combination of a car-body, hangers connected to and depending from said body adjacent to each side thereof, the lower and upper wheels arranged in the hangers and disposed in the direction of the length of the car,
- 10 the rods D arranged and adapted to move between the upper and lower wheels and having the vertically-disposed apertures b adjacent to their outer ends, coiled springs connected at one end with the car-body and at their opposite ends to arms on the rods, and the detachable fender proper having the frame comprising the section g provided with the tubular side bars j receiving the forward ends of
- 15

the rods D and having their forward ends flattened and provided with lateral lugs r, 20 the hooks k pivotally connected to the said side bars j and adapted to enter the apertures of the rods, and the section h connected in a hinged manner to the flattened ends of the side bars of the section g above the lugs r 25 thereof and adapted to fold back on the same, and netting or other suitable textile arranged within and connected to the frame, substantially as specified.

In testimony whereof I affix my signature 30 in presence of two witnesses.

JOHN ISRAEL NEWBURG.
